US0D1092615S

(12) **United States Design Patent** (10) Patent No.: **US D1,092,615 S**
(45) Date of Patent: ** Sep. 9, 2025

(54) **POINT OF SALE DEVICE**

(71) Applicant: **UST Global, Inc.**, Aliso Viejo, CA (US)

(72) Inventors: **Subhodip Bandyopadhyay**, Round Rock, TX (US); **Ramgopal Reddy**, Portland, OR (US); **Reema Siddarth**, Pune (IN)

(73) Assignee: **UST GLOBAL, INC.**, Aliso Viejo, CA (US)

(**) Term: **15 Years**

(21) Appl. No.: **29/833,023**

(22) Filed: **Mar. 31, 2022**

(51) LOC (15) Cl. **18-01**

(52) U.S. Cl.

USPC **D18/4.4**; D6/699
